Application filed October 21, 1886. Serial No. 216,912. Term of patent 14 years.

To all whom it may concern:

Be it known that I, LOUIS ANDRÉ FRÉDÉRIC BEN TAYOUX, a citizen of the French Republic, residing at Paris, in the Department 5 of the Seine, France, have invented and produced a new and original Design for a Musical-Scale Pointer or Indicator, of which the following is a specification, reference being had to the accompanying drawing, forming part 10 thereof.

In the accompanying drawing my musical-scale pointer or indicator is represented in plan.

The design of my scale-pointer consists in 15 a plate or tablet, Z, of any suitable material, of a rectangular shape, with its parts A and B wider or extending beyond both the upper and lower edges of the plate. These upper and 20 lower edges have projecting triangular pointers X, arranged as shown in the drawing.

The leading feature of my design consists in the triangular pointers, X, with which the up-

per and lower edges of the plate or tablet are furnished, together with the wider end portions, as shown. 25

I claim—
